SEALED LIGHTING UNIT AND ELECTRIC
INCANDESCENT LAMP THEREFORLorin W. Curtis, Verona, N. J., assignor to Tung-
Sol Lamp Works Inc., Newark, N. J., a corpora-
tion of Delaware

Application September 28, 1945, Serial No. 619,046

4 Claims. (Cl. 176—34)

1

This invention relates to sealed lighting units and incandescent lamps therefor.

More particularly this invention relates to the type of sealed lighting units wherein a reflector is soldered and sealed to the base of an electric incandescent lamp after the lamp is adjusted to bring the filament source into the desired focal relationship with the reflector, and one object of the invention is a novel and improved lighting unit of this character.

A further object of the invention is a novel and improved incandescent lamp for lighting units of the above indicated character which is characterized by its simplicity in construction, its low cost of manufacture and by its more satisfactory means of connection with the electric supply circuit.

Further objects of the invention will hereinafter appear.

For a better understanding of the invention reference may be had to the accompanying drawings illustrating one embodiment of the invention, wherein

Fig. 1 contains views illustrating a lighting unit embodying the invention;

Fig. 2 is a section along the line 2 of Fig. 1; and

Fig. 3 is a longitudinal sectional view through a socket usable with this lighting unit.

Referring to the drawings, the invention is illustrated as being embodied in a lighting unit comprising a reflector 1 and a lens 2, it being understood that the reflector 1 may be of any conventional projecting type and that the lens 2 may be of any conventional type. The reflector 1 and the lens 2 are joined together at their peripheral edges by any conventional watertight seal, the details of such seal being omitted for convenience in illustration. The reflector is provided with a circular opening in the back just large enough to accommodate the base 4 of an incandescent lamp 3, there being sufficient play between the reflector opening 1' and the base 4 to permit the adjustment of the lamp 3 to bring the filament 3' into the desired focal relationship with respect to the reflector 1. Upon arriving at such adjustment the lamp base 4 is mechanically fastened and anchored in position by means of a ring of solder 7 disposed about the periphery of the base at the outer edge of the opening formed in the reflector. This forms a water-tight seal between the reflector 1 and the outside surface of the base 4.

In the particular embodiment shown the base 4 is provided with a contact 5 at its end, rigidly

fixed and sealed in the end of the base, for supplying electrical energy to the filament 3', namely, to one end of the single filament 3' illustrated in the embodiment shown. For this purpose a leading-in wire 8 is electrically connected with the contact 5. The other lead-in wire for the filament 3' is grounded in any conventional manner to the base 4 and thence through the mechanical and electrical connection at 7 to the reflector 1.

The shell of the base 4 is of conventional form, namely closed at its outer end except for an opening for the reception of a conventional eyelet 5' to which the lead-in wire 8 is soldered 15 to form the contact 5. This eyelet and contact are insulatedly mounted within the opening formed in the end wall of the shell by means of any suitable insulating material as, for example, of glass 4', which is contained in the outer end 20 of the shell and is molded therein to form a glass insulator surrounding the eyelet and anchoring the eyelet and the contact 5 in fixed position. This mount thus forms a substantially water-tight seal at the outer end of the bulb. 25 The shell is also provided at its outer end with a fastening groove such, for example, as the groove 6 which forms a radial inwardly extending projection for anchoring or assisting in anchoring the insulator 4' within the outer end of the base. The insulating material 4' may be caused during the molding operation to flow only partially about the walls of the fastening grooves 6, 6' or wholly about them so long as it does not extend far enough to foul the sealed end of the bulb 3. Even a partial flow about these walls 30 is ordinarily sufficient to anchor the insulator 4' firmly against the inner surface of the outer end wall of the base and thereby to hold the eyelet 5' and the contact 5 firmly in operative position.

The metal at the groove 6 is not pierced so that the shell of the base 4 is imperforate throughout its outer peripheral surface. Moreover the groove 6 does not interfere with the adjustment of the lamp within the opening 1' of the reflector for focusing the filament 3' while the water-tight seal 7 may be formed and maintained as described above. The groove 6 thus performs the multiple functions of providing an attachment means for a socket or similar readily detachable connector, of anchoring or assisting in anchoring the insulating material 4' against relative movement in the shell, of enabling the free adjustment of the lamp base with 45 in the opening 1' of the reflector, of maintaining

the shell of the base 4 imperforate on its outer periphery, etc. The imperforate groove 6 may be easily and inexpensively formed in the shell of the base before the assembly of the base parts.

The imperforate groove 6 may be of any suitable character for facilitating the fastening of a detachable electrical connector to the lighting unit. In the particular embodiment shown this imperforate groove is J-shaped having a long stem part extending inwardly from the outer edge of the base longitudinally thereof and a right angle part merging with the stem part and an outwardly extending short part 6'. I have devised a quick and easily detachable connector 10 for connecting and disconnecting the source of electrical energy with the lamp 3. This connector comprises an outer shell having an inwardly extending pin or tit 17 which upon insertion of the connector over the projecting end of the base 4 is caused to enter the groove 6 and upon the pin or tit 17 reaching the innermost end of the stem part of the groove 6, the connector 10 is given a slight rotation to bring the tip or pin into the locking part 6' of the groove. The connector may be readily disconnected from the lighting unit by pushing inwardly on the connector 10 to bring the pin or tit 17 out of the locking part 6' of the groove and then giving the connector a slight reverse rotation to bring the tit into the outlet or stem part of the groove whereupon the socket may be removed by the straight pull away from the lighting unit.

As indicated above the member or part 17 may be either a pin riveted in position to project beyond the inner surface of the connecting shell or it may be a tit or indentation formed by pressing inwardly on the shell of the connector with suitable tools at this point. The latter is the preferable method because of its simplicity and low cost as this may be easily effected by machine and tool operations. A single fastening and anchoring groove 6 may be sufficient to firmly hold the connector 10 in operative position but there are illustrated a pair of these grooves disposed 180° from each other with a corresponding pair of tits 17 also spaced 180° from each other about the shell of the connector 10. The part of the shell 10 that telescopes the base 4 is formed with slots 12 which in turn form spring-like shell segments 11 frictionally gripping the base and facilitating the attaching, detaching and holding functions. In the particular embodiment shown there are four of these slots forming four segments 11 and these slots extend a sufficient distance to give the necessary spring gripping functions to the segments 11. The connector 10 embodies an electric wire cord 14 which has a disc contact member 14 for engaging and making firm electrical contact with the contact 5 of the lamp 3. This contact is maintained centrally of the connector and spring biased into contact with the contact 5 by the means illustrated comprising a disc 13 freely movable in the shell and through this disc 13 extends the stem of the contact 14 for centering the contact. On the side of the disc 13 opposite the contact 14 is disposed an insulating sleeve 15 and a biasing spring 16 engages this sleeve 15 at one end and engages the left-hand end of the shell of the connector at its other end. When the connector is connected and detachably fastened to the lamp base 4 the spring 16 biases the tit 17 into the locking part 6' of the anchoring groove and also presses the contact 4 firmly against the contact 5. The left-hand end 10' of the shell of the

connector is reduced in diameter as shown in the drawings.

I claim:

1. An incandescent lamp for a sealed lighting unit comprising a reflector having an opening therein for the reception of the lamp, said lamp having a base which is freely insertable through said opening and is sealable therein in fixed position with respect to the reflector with the end 10 of the base projecting beyond the reflector and adapted to receive a socket-like electrical connector, said base having a fixed contact on the end thereof for supplying electrical energy to the filament of the lamp when the connector is attached and comprising a shell which contains in its outer end and adjacent said fixed contact an insulating filler material and said shell having on its outer surface an inwardly formed groove anchoring said insulating means against relative movement in the shell and adapted to accommodate an attaching and holding device carried by said socket connector, said groove beginning at the end of the base shell and extending generally longitudinally of the base and leading to a circumferentially spaced attaching and locking groove part.

2. An incandescent lamp for a sealed lighting unit comprising a reflector having an opening therein for the reception of the lamp, said lamp having a base which is freely insertable through said opening and is sealable therein in fixed position with respect to the reflector with the end of the base projecting beyond the reflector and adapted to receive a socket-like electrical connector, said base having a fixed contact on the end thereof for supplying electrical energy to the filament of the lamp when the connector is attached and comprising a shell which contains in its outer end and adjacent said fixed contact an insulating filler material and said shell having on its outer surface an inwardly formed groove anchoring said insulating means against relative movement in the shell and adapted to accommodate an attaching and holding device carried by said socket connector, said groove beginning at the end of the base and having a guiding part extending generally longitudinally of the base, a rearwardly extending locking part circumferentially spaced therefrom and an intermediate arcuate part connecting the guiding part and the locking part.

3. A sealed lighting unit comprising a reflector having an opening in the rear thereof and a lens sealed on the front to close its cavity and substantially prevent the admission of moisture, an incandescent lamp assembly having a smooth cylindrical base freely insertable in said opening for adjustment relative to the reflector, said base extending through and beyond said opening for cooperation with a socket part, moisture sealing means retaining the base in its adjusted position in said opening to form a substantially hermetically sealed one-piece lighting unit, a fixed contact on the outer end of the base 60 for supplying electric current to the lamp when the socket part is attached thereto, and insulating means within said base for fixedly supporting the contact, said base and insulating means having on their outer surfaces corresponding inwardly projecting grooves cooperating one with the other to prevent relative movement between the base and said insulating material and for attachment of said socket part, comprising a guiding part beginning at the end of the base 65 and disposed substantially longitudinally there-

of, a rearwardly extending groove spaced therefrom and an intermediate arcuate groove connecting the inner ends of said longitudinal grooves.

4. A sealed lighting unit comprising a reflector having an opening in the rear thereof and a lens sealed on the front to close the cavity and substantially prevent the admission of moisture therein, an incandescent lamp assembly having a smooth cylindrical base freely insertable in said opening for adjustment relative to the reflector, said base extending through and beyond said opening for cooperation with a socket part, moisture sealing means retaining the base in its adjusted position in said opening to form a substantially hermetically sealed one-piece lighting unit, a fixed contact on the outer end of the base for supplying electric current to the lamp when the socket part is attached thereto, insulating means within said base for fixedly supporting the contact, said base and insulating means having on their outer surfaces corresponding inwardly projecting grooves cooperating one with the other to prevent relative movement between the base and said insulating material and for attachment of said socket part, said grooves comprising a guiding part beginning at the end

of the base and disposed substantially longitudinally thereof, a rearwardly extending groove spaced therefrom and an intermediate arcuate groove connecting the inner ends of said longitudinal grooves, and cylindrical socket means having a spring-mounted insulated contact including an electric wire attached thereto and inwardly projecting pins for cooperation with said grooves to removably hold the socket in position on said base and said removable contact in alignment with and bearing upon said fixed contact mounted in the base.
